INVENTOR:

James L. Turner
BY
E. J. Silvius.

ATTORNEY.

UNITED STATES PATENT OFFICE.

JAMES L. TURNER, OF INDIANAPOLIS, INDIANA.

LAWN-SPRINKLER.

SPECIFICATION forming part of Letters Patent No. 664,067, dated December 18, 1900.

Application filed July 26, 1900. Serial No. 24,748. (No model.)

To all whom it may concern:

Be it known that I, JAMES L. TURNER, a citizen of the United States, residing at Indianapolis, in the county of Marion and State 5 of Indiana, have invented certain new and useful Improvements in Lawn-Sprinklers; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 My invention relates to portable lawn-sprinklers, and has reference particularly to the nozzle whereby the spray may be produced, one object of the invention being to provide a simple, cheap, and durable sprinkling-nozzle which shall deliver considerable water rapidly and so as to spread and cover the maximum area without elevating the water objectionably in the air-currents.

20 A further object is to provide a sprinkling-nozzle which shall not be liable to derangement or damage through careless handling and which shall be free from such delicate parts as might become clogged and inoperative by accumulations from the water.

25 Referring to the drawings, Figure 1 represents a side elevation of my nozzle attached to a sled-shaped stand; Fig. 2, a perspective view of the nozzle; Fig. 3, a horizontal sectional view on a line X X in Fig. 1, showing 30 the upper end of the partitional wall or core which partly forms the spiral duct; Fig. 4, a vertical central sectional view of the complete nozzle, showing broadly its principal features; Fig. 5, a vertical central sectional view of the 35 nozzle-shell, the lower part of which is broken away and showing a modification in the details of construction; and Fig. 6, a view in elevation of the core substantially as it appears when formed separately from the nozzle-shell.

40 In construction I provide a suitable metallic nozzle-body A, of cylindrical form, having an enlarged open base a, in which are cut suitable threads e, adapted to engage either a 45 hose-fitting or a stand B, having an inlet-pipe elbow b and also a projection k, adapted to receive the base a. The body A has a cover

or cap C of circular flat form, in the center of which is an orifice d. If desired, the body may have a joint j near the cover C, in which 55 case one part of the body has external screw-threads m and the connecting part has internal screw-threads n, engaging the other threads and cut in an enlarged portion G, so that the interior of the chamber E may be 60 readily finished true and smooth separately if the core D is formed integral with the body A before attaching the cover to the body, and the cover may be removed at any time in order to attach an ordinary jet-nozzle to the 65 body.

In the body A is a core D, extending from a point h, near the lower or base end, to a point i, somewhat near the cover C, so as to leave an unobstructed circular chamber E below the cover, the core being in the form of a spiral thread projecting inwardly from the wall of the body A to about the center of its diameter, so that the wall of the body forms the outer confines of a spiral duct F, comprising 70 the space between the coils of the core. This partition or core D may be made integral with the body A, or the body may have a clear interior f and the core be made separately and pressed into the body and retained 75 by frictional resistance or otherwise.

It should be observed that the under face of the flat cover C is in a plane at a right angle to the axis of the nozzle, so that it acts as a baffle to the water as it emerges from the 80 duct.

In practical use the water enters the base and passes through the spiral duct F to the chamber E, in which it expands and is broken up, the spirality of the duct causing it to acquire 85 a centrifugal motion in the chamber, from which it is forced (the water being assumed to be under pressure) through the orifice d in a whirling spray in all directions radially and rising only to a moderate height. 90

Having thus described my invention, what I claim, and desire to secure by Letters Patent, is—

1. A lawn-sprinkler comprising a body portion having a cylindrical interior, a spiral core 95 rigidly attached to the interior of the wall of the body portion and extending inwardly from said wall toward, and substantially to, the axis of said body portion, and a cover having

an orifice therein removed from one end of such core, substantially as set forth.

2. A lawn-sprinkler consisting of a cylindrical body portion having screw-threads at 5 one end thereof and a cover having an orifice at the opposite end thereof, and a spiral core rigidly attached to the wall of said body portion and extending inwardly from said wall toward, and substantially to, the axis of said 10 body portion and longitudinally from a point near one end thereof to a point near the opposite end thereof, substantially as set forth.

3. A sprinkler-nozzle consisting of a cylindrical body having a smooth bore, a cover having 15 an orifice, and a core rigidly attached to the wall of said body and extending as a spiral

rib longitudinally of said body and inwardly toward and substantially to the axis thereof, whereby said core and the wall of said body together form a duct through said nozzle, substantially as set forth. 20

4. In a lawn-sprinkler, the spiral core D, the case or body inclosing said core and having the joint therein adjacent an end of said core, and a cap having the orifice near said 25 joint, substantially as shown and described.

In testimony whereof I affix my signature in presence of two witnesses.

JAMES L. TURNER.
